CLAIM

The ornamental design for a bottle and dosage cup, as shown and described.

DESCRIPTION

A portion of the disclosure of this patent document contains material which may be protected by copyright. The copyright owner has no objection to the facsimile reproduction by anyone of the patent document or the patent disclosure, as it appears in the Patent and Trademark Office patent file or records, but reserves all other copyright rights whatsoever.

FIG. 1 is a perspective view of a bottle and dosage cup showing my new design.

FIG. 2 is a plan view of one side of the embodiment shown in FIG. 1.

FIG. 3 is a plan view of the opposite side of the embodiment shown in FIG. 1.

FIG. 4 is a plan view of the top of the embodiment shown in FIG. 1; and,

FIG. 5 is a plan view of the bottom of the embodiment shown in FIG. 1.
